FABRIC TAKE-UP AND STOP MOTION DEVICE FOR KNITTING MACHINES

Application filed June 27, 1930. Serial No. 464,249.

This invention relates to knitting machines adapted to manufacture broad widths of cloth, and includes devices particularly useful in connection with circular machines of large diameter providing for a regulated tension of the fabric at the needles by imposing a take-up stress governed in accordance with the production of the machine; and further provides devices acting to stop the machine in case of improper operation, including a partial press-off of the fabric at a narrow segment or part of the periphery of the needles; and other cases of improper operation.

In knitting machines of the kind referred to, which are relied upon to produce broad widths of cloth for the cutting and sewing trades, it is usual to provide some form of take-up device for stressing the fabric in aid of the knocking-over function of the spring or latch needles relied upon to produce the fabric. Numerous expedients of the prior art for this general purpose exist in connection with machines in which the needle carriers are relatively stationary, but I am aware of no wholly satisfactory device for taking the fabric away from the needles which can be applied to machines in which a needle carrier or needle carriers rotate in respect to relatively fixed cams operating upon the needles to knit, which can also be relied upon automatically to stop the machine upon the occurrence of a cast-off or rupture of the fabric not substantially co-existent with the whole width of the fabric being made. When the machine is of the kind having a rotary needle cylinder or cylinder and dial, the fabric tube produced by the needles rotates with these needle carriers, and this implies providing a wind-up device for accumulating a convenient long length of the fabric; the take-up device proper, the wind-up device and connections for operating these devices, necessarily rotate in unison with the needle carrier or carriers producing the fabric, and devices operated in connection with the take-up for detecting undue slack in the fabric as a consequence of a press-off which could be relied upon, were the needle carriers stationary,

are not capable of being relied upon to cooperate with a rotary needle carrier or carriers. There is difficulty in providing an effective connection between the rotating elements associated with the take-up and the devices for driving the rotary elements of the machine which shall operate in any rotative position of the needle carrier, take-up and winding devices to cause cessation of driving movement upon the occurrence of a press-off at any regular position of the take-up, needle carrier and wind-up device.

One object of this invention is to provide a simple and reliable organization for putting a regulated stress on the fabric to take it away from the needles, which shall be sensitive to slack operating in a limited segment of the course of fabric normally hanging from the needles upon which it is knit, and to provide responsive devices transmitting an operative impulse to the driving devices of the machines to stop the machine when the fabric yields unduly at any part of the course being knit. Another object of the invention is to provide improved means for maintaining this stress on the fabric in accordance with its production, so that in normal operation a steady take-up stress is a consequence of the growth, whereas undue yielding to the said stress automatically determines stoppage of the machine. Another object of the invention is to provide for mounting and driving a wind-up roll consistently with reliance upon a take-up device between the needles and the wind-up roll for the above purposes. Another object of the invention is to provide for automatically resetting the stop motion devices prior to resuming knitting operation after an automatic stoppage for any purpose; and a further object of the invention is to provide an improved way for making the indications of stop motion feelers at the needles effective to stop the machine, and to reset these connections after a stoppage from this cause.

The invention will now be explained in connection with preferred species of mechanism embodying it shown in the accompanying drawings, in which

Fig. 1 is an elevation partly in radial sec-

10

tion through certain frame and bearing elements of the machine on the line 1-1 of Fig. 2;

Fig. 2 is a plan of devices shown in Fig. 1, partly in section to display a take-up frame and rolls;

Fig. 3 is a left side elevation of a pivoted take-up frame, rotary ring and mounting, showing a part of the connections to the stop-ping devices;

Fig. 4 is a detail similar to Fig. 3 showing the parts in a position caused by depression of the take-up frame;

Fig. 5 is a fragmentary plan of parts shown in Fig. 3;

Fig. 6 is a detail vertical section through a driving clutch mechanism for the take-up rolls;

Fig. 7 is a right side elevation of the driving connection for the take-up rolls through the clutch devices shown in Fig. 6;

Fig. 8 is a section in elevation on a radial plane showing connections for stopping the machine through indication of a feeler at the needle heads; and

Fig. 9 is a detail side elevation showing a connection between the stop motion knock-off devices and stop motion feelers at the needles.

Referring now to Fig. 1, the illustrative machine may comprise any usual kind of frame having legs 1, an upper table 2 on which there may be a bearing, for example at 3, for a rotary needle cylinder 4, which table will provide a convenient support for a cam ring 5 containing any suitable kind of knitting cams for actuating needles, not shown, in slots in the bed or carrier 4. If desired the machine may be provided with a dial 6, the dial supporting a dial cam cap of any desired kind to provide for knitting upon a radially disposed series of needles; the dial may carry other instruments of any kind for any usual purpose.

In the form shown the legs 1 support a lower table 10 spaced from the table 2. The table 10 may be a substantial ring of metal carrying on its upper face any kind of suitable columns or supports 11 for the upper table 2. As shown, one of these supports 10 may be provided with a bearing boss 12 bored for a main drive shaft 13, which may have an outboard bearing or bearings at 14 and 15 in a bracket 16 fastened to the column 11. As usual, the shaft 13 supports a normally loose pulley 17 for a driving belt, which may have on its outer end a hand wheel 18, and is provided with a splined clutch element 19 having an operating collar 20 and connected to any usual or preferred type of clutch and brake member adapted to be operated by sliding the collar 20 to the left to grip the pulley 17 to the shaft 13, and to the right to release the pulley 17 from the shaft 13. The inner end of the shaft 13 carries a bevel pin-

ion 21 meshing with a gear ring 22 bearing at 3 on the frame 2, said ring having an annular seat for the needle cylinder 4.

To stop and start the machine the clutch collar 20 is moved by a yoke 25 operated by 70 a hand lever 26.

In a preferred arrangement the lever 26 is moved to the left manually to start the machine, and moved to the right automatically by compression spring 27 surrounding a 75 trip rod 28 passing through a hole in the column 11 and having a notch on the far side (Fig. 9) for a trip lever 29, operated by gravity or hand to engage the notch and hold the trip rod 28 during normal operation of 80 the machine. The lever 29 is arranged to be lifted out of the notch in the rod 28 upon the occurrence of any of the faults of operation for which it is desired to stop the machine. When the hand lever 26 is moved to the right, the clutch element 19 may as usual be operated upon by a fixed element of the bearing 15 to brake the machine parts (not shown). Any other suitable machine brake 85 operated upon release of the rod 28, may of course be employed.

In the normal operation of the machine, fabric knit at the needles and passing over the verge at the top of the cylinder 4 is required to be given as even a stress downwardly as possible and to this end is arranged to be operated upon by take-up rolls 30, 31 of any usual kind, Figs. 1, 2, 3 and 7, adapted to tension the fabric by gravity or gravity modified by the function of a spring. As shown, (Fig. 3) roll 30 is mounted in bearings in a frame 32 pivoted at 33 in brackets 34 on a rotary ring 35 which may be as shown, a circular rack having external teeth at 36 and having a depending flange 37 bearing in an annular recess in the table 10, engaging at one point of the periphery of the machine with a pinion 40 (Fig. 1) on a vertical shaft 41 driven by a bevel gear 42 within a depending bearing bracket 43 for the shaft 41, which bearing bracket also provides a bearing for a shaft 44 carrying a bevel gear 45 meshing with the bevel gear 42, and has fast thereon a bevel pinion 46 engaging and driven by the gear ring 22. The gear ratio of the system 40, 41, 42, 45, 46, 22 is such as to drive the ring 35 at the same angular velocity as the cylinder 4.

In the preferred form shown, the pivoted frame 32 with the take-up rolls 30 and 31 may comprise two symmetrical opposite ends, of which only the right-hand member is shown in Fig. 2, rigidly attached to the pivot shaft 33 and to a stiffening rod 32^a. One of the heads of the frame 32 may be extended as shown at 32^b. Fig. 7, to receive a pivot 32^c for a hold-down rod 32^d which passes through a bore in the gear ring 35 and is provided on the under side of the table with a compression spring 32^e held in place by a nut 32^f.

The rod 32^a and spring 32^b may act as a limit stop to prevent the take-up frame 32 from taking too extreme a position under the weight of the rolls 30 and 31, which overbalance the spring 32^b except when the spring is considerably compressed.

The idler take-up roll 31 preferably has reduced bearing spindles bearing in holes in blocks 31^a sliding in the frame 32 under the influence of compression springs 31^b housed in the cap 31^c.

Referring now to Figs. 1, 2, 6 and 7, the roll 30 is driven by a worm wheel 50, on a reduced end of the roll 30 projecting through a bearing hole in the frame 32, worm wheel 50 being driven by a worm 51 having a bearing in a bracket 52 integral with or attached to the frame 32, the worm 51 having a reduced end integral with or attached to a bevel pinion 53 meshing with a bevel pinion 54 on the projecting end of the pivot shaft 33 for the frame 32. The pinion 54 is driven by a bevel gear 55 on the upper end of a vertical shaft 56 (Fig. 6) having a bearing in a vertical hole in the projection 34^a of the bearing bracket 34^b for the pivot shaft 33 of the take-up frame. The projection 34^a carries bored depending lugs 34^c in which is mounted a fulcrum pin 34^d for a lever 75 presently described. The shaft 56 further finds a bearing in an anti-friction bushing 57 loose in a hole in the gear ring 35, on which the bracket 34^a etc. is mounted, said shaft 56 also having a bearing in a hole in a pinion 58 having a reduced hub 59 bearing in a bushing 60 mounted in a depending oil cup bearing 61 of a bracket 62 mounted on the lower face of the gear ring 35. Shaft 56 has a shoulder 56^a bearing against an internal shoulder in a hole in the pinion 58, the hub of which is faced off at 58^a to bear on the top of the depending bracket 61.

The bushing 57 is vertically movable on the shaft 56 for the purpose of transmitting operating impulses to a friction clutch, preferably of the multiple-disk type and preferably housed in a recess within the pinion 58. The pinion 58 is the primary drive connection for the train of gearing ending at the take-up roll 30, and may be driven suitably as shown, by planetary revolution within a fixed internal gear ring 63 mounted on depending lugs 64 at suitable intervals on the under side of the fixed table 10.

Driving impulses of the shaft 56 through the gear 58, as controlled by the vertical position of the bushing 57, will be transmitted through the clutch within the pinion 58. As shown the pinion 58 is cut out on the top to provide a recess having a longer diameter in which screws 65, holding in place a cover plate 66, takes into notches in projecting ears 67 of clutch plates thus held to rotate with the pinion 58 and between vertically free intervening clutch plates having internal

lugs projecting into key-ways 68 of the shaft 56, to be put into frictional contact with the clutch disks 67 by a vertical impulse transmitted to the pile of clutch disks by a compressor plate 69 upon which rests a collar 70 which may in turn support bearing balls and the other member 71 of a thrust transmitter connection which preferably includes a light compression spring 72 and a screw collar 73 on the lower end of the bushing 57.

The bushing 57 is acted upon by lugs 74 of the lever 75, which is forked to straddle the shaft 56, which lugs bear on diametrically opposite points of the plane face of the bushing 57. The lever 75 may have an adjustment screw 76 and lock nut taking against the under face of a wear plate 77 on the frame 32.

These arrangements are such that downward motion of the take-up frame 32 in response to the growth of the fabric pinched between the rolls 30 and 31, exerts pressure through the lever 75 and lugs 74 on the friction clutch 67, etc., and results in operation of the roll 30 until the frame 32 has risen to a predetermined point. The fabric pinched between the rolls 30 and 31 may be spread by any usual form of internal spreader 180 mounted on any overhead rotary structure of the machine, such as the dial 6.

A sufficient driving impulse is transmitted through the clutch and shaft 56 when the spring 72 has been placed under a light compression by the operation of the movable bushing 57 and the lever 75. But the spring 72 is capable of further compression to accommodate a still lower position of the take-up frame, such as will occur when the weight of the heavy take-up rolls is not counterbalanced to a normal degree by the resistance of the fabric-tube hanging from needles at the verge of cylinder 4 throughout the periphery of the tube. The stress transmitted through the fabric will be lessened by any rupture of the forming course on the needles at the cylinder verge or gap in the knitted fabric adjacent the forming course, and the take-up frame is free to move downwardly below a normal position whenever this occurs through any substantial extent of the length of the forming course. This motion downward is utilized to stop the machine to prevent its operation before the press-off can extend further than is necessary to induce the motion of the take-up roll frame.

It is therefore provided that motion downward of the frame 32 beyond a predetermined point shall determine stoppage of the machine after motion of the parts in this position through a predetermined short angle of rotation. While the devices for this purpose may be any devices establishing a connection to be operated by the displacement downward of the frame 32, a preferred construction comprises a transmitter ring 80, prefer-

ably of L-shaped cross section, mounted to rotate on the upper surface of the gear ring 63, Figs. 1, 3, 4, 5 and 7. If desired the ring 80 may be housed in an annular groove, or, as shown, be held in place by occasional stop screws 81, with respect to which the ring 80 has freedom of motion to the extent of cuts 82 in its flange. The ring 80 is notched on its upstanding member as at 84, the notches having sloping edges, and being separated from each other by suitable angular distances less than the extent of permissible rotation of the machine after the occurrence of the press-off and before stoppage.

15 The ring 80 is stressed in a direction opposite to the direction of rotation of the take-up frame by a suitable light spring or springs 85 reacting between pins on the flange of the ring 80 and pins fixed in the gear ring 63, Figs. 3 and 4.

In order to transmit to the ring 80 motion in the direction of rotation of the take-up frame for the purpose of stopping the machine by connections to be described, one of the heads of the frame 32 carries a link 86, which may be made in two parts to be adjustable in length, having an end 87 provided with a slot 88 of sufficient length and position to determine the downward permitted free motion of the frame 32 without any actuation of the stop motion ring 80.

An arm 143 which is mounted on and extends downwardly from the gear ring 35 may serve to carry suitable mechanism for actuating the stop motion ring. Mounted on this arm on a pivot 90 there may be provided an actuator lever 91 having a radially projecting pin 91^a to take into any of the notches 84 and a nose 92 adapted to engage under an adjustable latch end 93 of a holding lever 94 which comprises a short shaft 95 journaled in a hole in the arm 143, and an inner end 96 having an inwardly projecting pin 97 taking into the slot 88 of the link 86, 87.

45 The actuator lever 91 is preferably downwardly stressed by a light spring 98 and the latch lever 93, 94, 95, 96 may be stressed downwardly by light spring 99. These arrangements are such that whenever the pin 91^a of the actuator lever is dropped, it moves ring 80 until the ring is stopped, whereupon the actuator rides out of the notch. When the actuator is lifted and the take-up frame 32 has been raised again to within its normal range of positions, the latch 93 may take over the nose 92 and hold the lever 91 lifted until the link 86, 87 again depresses the pin 97.

The relation of actuator 91, 92 to the cam-sides notches 84 permits resetting the parts after the ring 80 has been moved to determine stoppage, by moving the ring back on the gear 63 to its original position. This may be the function of the spring 85 only, reacting on the pin 91^a through the cam slopes of any of the slots 84, but it is preferred to

make the resetting motion dependent upon the proper positioning of the knock-off parts and to that end, Figs. 3 and 5, the ring 80 may carry limit stops 101, 101 between which one end of a lever 102, pivoted on a bracket 103 on the outer face of the gear ring 63, may take.

The other end of lever 102 takes into a notch on a drop rod 105 free in a hole in the bracket 103; this rod 105 is caused to drop by moving the latch 102 when the ring 80 is picked up by the actuator pin 91; the rod 105 having dropped, the latch 102 and ring 80 can not be returned to initial position until the rod 105 has been lifted.

Rod 105 passes through a hole in the right end of the knock-off lever 29, Figs. 2 and 9, and beyond the upper face of the lever 29 is provided with an adjustable stop collar 106. Unless the knock-off rod 28 has been moved to the left, Figs. 1 and 2, to bring its notch under the knock-off lever 29, the rod 105 will not be lifted far enough to bring its notch over the latch lever 102. Therefore, the operator of the machine can not reset the stop motion without engaging the knock-off rod 28 in proper position for automatic operation; nor can the rod 28 and lever 29 be properly positioned without resetting the stop motion devices comprised of the ring 80 and connection to the frame 32.

The devices described provide for stopping the machine within the angular rotation represented by the distance between the notches 84 in the ring 80 on the occurrence of the press-off. There are, however, other occasions on which it is desirable to stop the machine; for example, the breakage or replacement of a needle, the improper position of a needle latch, or the accumulation of yarn or waste fiber in the needle throats. It is well known in the art to detect these faults by a detector such as the pointed feeler 110, Fig. 8, which may be displaced with a vertical shaft 111 in a bracket 109 upon the occurrence of any of the mentioned faults of the operation. In the form shown, shaft 111 is provided with a latch 112 taking against a shoulder at the upper end of a short shaft 113 stressed upwardly by a compression spring 114 in the table 2 reacting on the under side of a fixed collar 115 and against the top of a bushing 116 in which the shaft 113 has a bearing. There are as many brackets 109 and detectors 110, shaft 113 etc., as desired about the machine; for example, as many as there are knitting waves or feed points.

The upward motion of the shaft 113 when the latch 112 is released by the operation of the feeler 110 is relied upon to cause the rotary element of the machine to work the lever 29 and knock-off rod 28 to stop the machine. Referring to Fig. 8, shaft 113 carries an arm 117 having an end bored to slide on a stud 118 projecting downwardly from table 130

2. On the stud 118, and adapted to be moved against gravity by motion of the arm 117, a two-armed rocker 119 can slide from the position shown in Fig. 8 upwardly, whenever the shaft 113 is released, to bring the rocker 119 into contact with one or more of the operating studs 120 screwed into the under side of the gear ring 22 rotating with the cylinder 4. Encounter of the rocker 119 with one of the pins 120 is relied upon, through contact with a stud 121 projecting from a stop motion annulus 122 in an annular groove on the under side of table 2 to move the annulus 122. As best shown at Fig. 9, annulus 122 may carry a cam 123 to react with a bell-crank lever 124 on a bracket 125 depending from the table 2 to ride down the right-hand end of the knock-off latch lever 29 and so determine stoppage of the machine.
- The ring 122 may be reset by hand, but in the preferred construction, see Fig. 1, the rear end of the clutch shifting lever 26 is provided with a slotted link 130 operating a two-armed lever 131 to pull on a wire link 132 and actuate a horizontal bell-crank lever 133 taking against one of the studs 121 on annulus 122 to move it back to its normal position whenever the lever 26 is manually reset again to start the machine in motion.
- Referring now to Figs. 1 and 7, the fabric produced in the machine is wound up on a cylindrical core 140 having a spindle 141 free to rise and fall in a slot 142 in each arm of a bracket comprising diametrically opposite arms 143 fastened to the under side of the ring 35, and rotating with the take-up rolls and needle bed. The fabric roll on core 140 is driven at a constant surface speed less than the normal driving speed of the take-up rolls 30, 31, to avoid tension on the fabric between the take-up rolls and wind-up roll to a degree having a material effect on the vertical position of the take-up rolls, as compared with the effect of the tension of the fabric between the needles and the rolls 30, 31. One way of doing this is, as shown, to provide traction rolls 145, 146 journaled in the arms 143 above a brace rod 147 connecting the arms 143 rigidly, said rolls 145, 146 having extended reduced ends bearing gears 148, 149 meshing with a gear 150 attached to a worm-wheel 151 driven by a worm 152 at the lower end of a shaft 153 in brackets on arm 143, and having a pinion 154 at its upper end meshing with gear ring 63. The lower bracket may provide a box for the gear train. The winding fabric roll rests on the web passing within and above the rolls 145, 146. The web may pass around the member 147 if desired. As will be understood by those skilled in the art, the friction of rolls 145, 146 pre-determines winding at a constant surface speed and a constant limit of tension at which the rolls 145, 146 will slip. If the fabric is passed around the strut member 147,

a full roll may be removed and core 140 inserted without releasing the fabric from contact with the winding friction surfaces.

I claim:

1. Fabric take-up and stop-motion device for use in knitting machines having rotating fabric-producing elements comprising in combination, rolls for drawing the fabric away from the fabric-producing element mounted for freedom of motion in response to varying tension on the fabric; means for operating the rolls for drawing off the fabric according to the position of said rolls as controlled by said tension; means causing the said rolls to rotate in unison with the fabric-producing element about an axis at an angle to said rolls, a driving connection for the machine adapted to be released, and means operating as a consequence of the bodily movement of the rolls when the tension on the fabric permits recession of the rolls from the fabric-producing elements to a predetermined degree to release said driving connection.

2. Fabric take-up and stop-motion device for knitting machines having therein in combination a rotary needle-bed and knitting devices, a frame having vertical freedom of motion and take-up rolls therein, and means for causing said frame to rotate in unison with said needle-bed, means for driving a take-up roll controlled by the vertical position of said frame within certain limits, a driving connection for the machine parts adapted to be released, and means including a connection free to rotate through a limited angle with said frame adapted to be operated upon the occurrence of a predetermined vertical position of said frame for releasing said driving connection.

3. Fabric take-up and stop-motion device for knitting machines having therein in combination a rotary needle-bed and knitting devices, a web take-up device adapted to impart tension to the knitted web, means for causing said take-up device to rotate in unison with said needle-bed, means for driving the take-up device controlled by the vertical position of said take-up device, a releasable driving connection for the machine parts, a normally stationary member actuatable to release said driving connection, and an actuator rotating in unison with the take-up device and operatively connected thereto for movement into actuating engagement with said normally stationary member to release said driving connection upon recession of the take-up device from the fabric producing elements to a predetermined degree.

4. Fabric take-up and stop-motion device for use in knitting machines having rotating fabric-producing elements comprising in combination, take-up rolls for drawing the fabric away from the fabric-producing element mounted for freedom of motion in re-

sponse to varying tension on the fabric; means for operating the rolls for drawing off the fabric according to the position of said rolls as controlled by said tension; means for 5 winding the fabric in a roll at a constant surface speed; means causing the said take-up rolls and winding means to rotate in unison with the fabric-producing element about an axis at an angle to said rolls, a driving connection for the machine adapted to be released, and means operating as a consequence 10 of the rotation of the rolls when the tension on the fabric permits recession of the rolls from the fabric-producing elements to a predetermined degree for releasing said driving connection.

5. In a web take-up for knitting machines having a rotary needle-bed, a frame movable along the axis of said needle-bed and take-up 20 rolls, and means for rotating said frame in unison with the needle-bed on a common axis therewith, a shaft, and a gear train for driving one of the take-up rolls comprising a pinion driven from a stationary annulus, said 25 shaft and pinion being respectively fast to clutch elements adapted to be engaged and disengaged by stresses in the direction of said shaft, a lever in contact with said frame for operating said clutch, a spring between said 30 clutch elements and lever, whereby said frame has freedom of motion beyond its range for operating said clutch, and a link and connections for stopping the machine operative at one position of said frame within 35 said freedom of motion.

6. In a web take-up for knitting machines having a rotary needle-bed, a take-up device of which the web-engaging part is capable of bodily movement approximately along the 40 axis of the needle-bed, means for rotating said take-up device in unison with the needle-bed on a common axis therewith, a shaft and a gear train for driving the take-up device to impart tension to the web of knitted fabric, said train comprising a pinion driven from a stationary annulus, a clutch in said 45 train for determining transmission of motion from said pinion to said take-up device, connecting means for causing engagement of the clutch upon recession of the web-engaging part of the take-up device from the fabric-producing elements, said connecting means including a yieldable element whereby the 50 take-up device has freedom of motion beyond its range for operating said clutch, and means actuatable by said take-up device upon further recession from the fabric-producing 55 elements for stopping the machine.

7. Stop-motion for rotary-needle bed knitting machines having a rotating web take-up with axial freedom of motion in response to web tension, comprising in combination power release devices, a ring connection surrounding the axis of rotation of the web take-up, a latch for said power release devices, and

a connection therefrom to said ring connection, and means rotating with said take-up adapted to contact with and rotate said ring connection to work said latch on the occurrence of abnormal slack in the web. 70

8. Stop-motion for rotary-needle bed knitting machines having a rotating web take-up comprising a driven roll in a frame having axial freedom of motion in response to web tension, comprising in combination power release devices, a notched ring connection surrounding the axis of rotation of the web take-up, a latch for said power release device and a connection therefrom to said ring connection, and an actuator rotating with said take-up adapted on response of said frame to slack web to contact with a notch in and rotate said ring connection to work said latch. 75

9. Stop-motion for rotary-needle bed knitting machines having a rotary web take-up with axial freedom of motion in response to web tension, comprising in combination a power release device, a ring having cam-sided notches surrounding the axis of rotation of the web take-up, means operable by movement of the ring to actuate the power release device, an actuator rotating with the take-up and yieldingly urged into operative engagement with notches in the ring to move the ring, a holding device normally in position to hold said actuator out of operative engagement with the notches of the ring, and a connection between said holding device and said take-up effective upon abnormal movement of the take-up for moving the holding device to release the actuator and allow the actuator to enter a notch in the ring to move the ring, a cam side of the notch thus engaged restoring the actuator to a position to be engaged by the holding device upon return of the take-up to a normal position. 90

10. Stop-motion for rotary-needle bed

knitting machines having a rotating web take-up with axial freedom of motion in response to web tension, comprising in combination a power release device, a ring connection surrounding the axis of rotation of the web take-up, a latch for said power release device and a connection therefrom to said ring connection, and means rotating with said take-up for contacting with and rotating said ring connection to release said latch on the occurrence of abnormal slack in the web, said means including an actuator yieldingly urged toward operative engagement with said ring, a holding device normally preventing such operative engagement, and a connection between said holding device and said take-up for moving the holding device to release the actuator upon abnormal movement of the take-up. 110

11. Stop-motion for rotary-needle bed knitting machines having a rotating web take-up with axial freedom of motion in re- 115

- sponse to web tension, comprising in combination a power release device, an actuator member rotating with the take-up, normally stationary means for receiving actuating impulses from said actuator in any of a plurality of angular positions of the take-up and needle bed, an operative connection between said normally stationary means and the power release device, a holding device effective while the take-up occupies normal positions to hold the actuator out of impelling engagement with said normally stationary means but ineffective in abnormal positions of the take-up, a stop limiting the movement of the said impulse-receiving means, said impulse-receiving means including cam surfaces adapted to disengage the actuator and return it to a position to be held by said holding device.
12. A stop-motion for a rotary-needle cylinder knitting machine comprising a fabric engaging detector rotatable bodily with the needle cylinder, said detector under normal conditions of knitting being positioned between predetermined planes but dropping below the lowest of said planes upon the occurrence of abnormal slack in the knitted web, drive mechanism for the needle cylinder comprising a power release latch, and means including a ring coaxial with the needle cylinder for transmitting abnormal downward movement of the detector, occurring at substantially any angular position of rotation of the needle cylinder, to the power release latch to actuate the latter.
13. In a stop-motion device for knitting machines, a rotary web take-up, a ring surrounding said take-up, an actuator operable by said take-up and adapted to be positioned by response of said take-up to slack in said web to contact with and move said ring, and power release devices having a latch connected to be worked by said ring when moved by said actuator.
14. In a stop-motion device for knitting machines, a rotary web take-up, a ring having cam sided notches surrounding said take-up, an actuator on said take-up adapted to be positioned by response of said take-up in said web to enter one of said notches and move said ring, and to react with the notch entered to be subsequently released, and power release devices having a latch connected to be worked by said ring when moved by said actuator.
15. In a stop-motion device for knitting machines, a rotary web take-up, an actuator movable bodily with the take-up, means for normally holding said actuator in an inoperative position, said means being releasable by response of said take-up to slack in the knitted web, a normally stationary ring surrounding said take-up, said ring being engageable by and movable by said actuator when the latter is released, a power release device, and a latch for the power release device operatively engageable by said ring to be moved by the ring when the ring is moved by the actuator.
16. In a stop-motion device for knitting machines, a rotary web take-up, a ring surrounding said take-up, an actuator operable by said take-up and adapted to be positioned by response of said take-up to slack in said web to contact with and move said ring, a lever connected to said ring for limited movement therewith, a rod latched against motion by said lever, and power release devices adapted to be worked by said rod.
17. In a stop-motion device for knitting machines, a rotary web take-up, a ring having cam sided notches surrounding said take-up, an actuator operable by said take-up and adapted to be positioned by response of said take-up to slack in the knitted web to enter one of said notches and move said ring, and to react with the notch entered to be subsequently released, a lever connected to said ring for limited movement therewith, a rod latched against motion by said lever, and power release devices adapted to be worked by said rod.
18. In a stop-motion device for knitting machines, a rotary web take-up, a ring having cam-sided notches surrounding said take-up, an actuator operable by said take-up and adapted to be positioned by response of said take-up to slack in the knitted web to enter one of said notches and move said ring and thereafter to be released from the notch by the action of the cam-side of the latch, a latch movable by said ring as the ring is moved by the actuator, a drop rod normally held by said latch but released therefrom upon movement of the latch by the ring, a knock-off rod and a power release clutch control, means for urging the knock-off rod to move in a direction to release the clutch to stop the machine, and a knock-off lever controlled by the said drop rod and engageable in one position with the knock-off rod to prevent release of the clutch during normal operation.
19. In a stop-motion device for knitting machines, a rotary web take-up, a ring having cam-sided notches surrounding said take-up, an actuator on said take-up adapted to be positioned by response of said take-up to slack in said web to enter one of said notches and move said ring, and to react with said notch to be released therefrom, a spring opposing motion of said ring, a lever having an end between limit stops on said ring; a rod latched against motion by said lever, and a power-release device worked by said rod; said rod having a part holding said lever and notched ring against resetting until said rod is restored to normal position.
20. In a knitting machine, in combination, a web take-up, and actuator means respon-

sive to slack web thereat, a power release device having a controlling trip and connections adapted to be operated by said actuator means to work said trip, devices for 5 detecting abnormal conditions at the needles in said machine, and means operated by said detecting devices for working said trip.

21. In a knitting machine having a rotary needle-bed, means rotatable in unison with the 10 bed for imparting a tension to the axially moving knitted web, said means being adjusted to impart an approximately uniform tension to the web in normal perfect knitting, mechanism rotatable in unison with the 15 needle-bed and movable axially in one direction in response to diminution of tension in the web and to growth of the web, means for moving said mechanism in the opposite direction to maintain it within a normal range 20 of positions during growth of the web in normal perfect knitting, said means being ineffective at least momentarily to restore said mechanism to its normal range of positions upon such diminution of tension of the web 25 as is caused by a gap adjacent the forming course of fabric, a power release device, and means for causing operation of the power release device when said mechanism moves out of its normal range of positions.
- 30 22. In a knitting machine having a rotary needle-bed, means rotatable in unison with the bed for imparting a tension to the knitted web, mechanism rotatable in unison with the needle-bed and movable axially in one 35 direction in response to axial progression of the web, means for moving said mechanism in the opposite direction to maintain it within a normal range of positions during growth of the web in normal perfect knitting, said 40 means being ineffective at least momentarily to restore said mechanism to its normal range of positions upon such abnormal progression of a portion of the web as is caused by a gap adjacent the forming course of fabric, a 45 power release device, and means for causing operation of the power release when said mechanism moves out of its normal range of positions.

50 Signed by me at New York, N. Y., this 24th day of June, 1930.

HARRY SWINGLEHURST.
